C. BUCK

SPARK PLUG WRENCH

Filed Sept. 14, 1921

Fig. 2

INVENTOR.
Charles Buck.
BY *William Jackson*
ATTORNEY.

UNITED STATES PATENT OFFICE.

CHARLES BUCK, OF GERMANTOWN, PENNSYLVANIA.

SPARK-PLUG WRENCH.

Application filed September 14, 1921. Serial No. 500,701.

To all whom it may concern:

Be it known that I, CHARLES BUCK, a citizen of the United States, residing at the city of Germantown, county of Philadelphia, 5 and State of Pennsylvania, have invented a certain new and useful Spark-Plug Wrench, of which the following is a specification.

This invention, generally stated, relates to internal combustion engines as used in 10 motor-vehicles, motor-boats, aeroplanes, and otherwise and has more especial relation to a wrench with which to remove certain bolts to disengage the head from the cylinder and with which to remove certain of the spark- 15 plugs.

The leading object of the present invention is to provide a wrench of simple and efficient structure; of comparatively inexpensive design, and of compact form which 20 may be employed for removing the nuts of bolts of the cylinder-head and which may be employed for removing the spark-plugs.

The invention consists of the improvements hereinafter described and finally 25 claimed.

The nature, characteristic features, and scope of the invention will be more fully understood from the following description taken in connection with the accompanying 30 drawings forming part hereof, and in which;

Fig. 1 is a front elevational view of the tool, and

Fig. 2 is an edge view thereof.

For the purpose of illustrating my invention I have shown in the accompanying drawings one form thereof which is at present preferred by me, since the same has been found in practice to give satisfactory 40 and reliable results, although it is to be understood that the various instrumentalities of which my invention consists can be variously arranged and organized and that my invention is not limited to the precise 45 arrangement and organization of the instrumentalities as herein shown and described.

In the drawings the tool is shown as being of integral structure and generally stated comprises a stem provided at one end with 50 a substantially ring-like handle equipped with oppositely disposed nut-engaging portions and provided at its other end with a spark-plug socket engaging portion the whole forming a substantially T-shaped device. The stem is designated 10 and termi-

nates at one end in a handle 11 which is disposed at right angles to said stem and is of the general configuration of an elongated eye. The opposed ends of the handle are provided with nut-engaging or wrench-parts 60 12 and 13, of which the one designated 12 is smaller than other and is adapted to fit the nuts of a cylinder-head, and of which the one designated 13 is adapted to engage the nuts of spark-plugs. In practice several 65 sizes of tools are made to accommodate different types of engines. The wrench-parts are disposed in the same plane upon an axis extended through the handle at right angles to an axis extended through the stem. The 70 wrench-parts extend beyond a line circumscribing the handle ends. The ring-like portion of the handle enables the operator to obtain a good grip when using the tool as a cylinder-head lifter. The opposite end of 75 the stem terminates in an enlarged cylindrical portion 14 exteriorly screw-threaded for engaging a socket from which a spark-plug has been removed. In practice when a cylinder-head requires moving the nuts of bolts 80 securing the head to the engine block are loosened by wrench-parts 12 of the tool and removed, and at least two spark-plugs removed after being loosened by wrench-parts 85 13. Two of these tools are then employed 90 for removing the cylinder-head, a part 14 of each being fitted to a socket previously occupied by a spark-plug. The operator grasps a tool handle in each hand and thus may readily remove a head. As the cylinder-heads are frequently hot this affords an 95 efficient and expeditious manner of removal.

What I claim is:

A spark-plug wrench having a handle comprised of a single elongated cylindrical stem which extends throughout the major portion of its extent upon straight lines to provide a smooth hand-grip, said stem having formed integral therewith at one end thereof a flattened body extending at right angles to and upon each side of said stem to complete a T-shaped structure, the opposite ends of said body being each provided with a wrench-part, which wrench-parts are arranged in the same plane and which project beyond a line circumscribing the opposed ends of said body portion.

In witness whereof I have hereunto signed my name.

CHARLIE BUCK.
